UNITED STATES PATENT OFFICE.

MERTON P. STEVENS, OF EAST ORANGE, NEW JERSEY, ASSIGNOR TO THE SAFETY CAR HEATING AND LIGHTING COMPANY, OF NEW JERSEY.

GAS-LAMP.

SPECIFICATION forming part of Letters Patent No. 645,142, dated March 13, 1900.

Application filed January 4, 1898. Serial No. 665,506. (No model.)

To all whom it may concern:

Be it known that I, MERTON P. STEVENS, a citizen of the United States, residing at East Orange, State of New Jersey, have invented 5 new and useful Improvements in Gas-Lamps, of which the following is a specification.

My invention relates to light-giving apparatus, and more especially consists of an improved form of suspension-lamp to be employed in burning gas or oil. The lamp is regenerating in its action and is especially designed to produce an effective heating of the air taken in for combustion, at the same time protecting the flame from all side and back drafts or other air-currents tending to produce a fluctuation of light.

The preferred form of lamp is illustrated in the accompanying two sheets of drawings, in which—

20 Figure 1 is a vertical central section, and Fig. 2 is a horizontal section taken on lines 2 2 of Fig. 1.

Throughout the drawings like reference-figures refer to like parts.

25 1 is a supporting-frame generally, which consists of the ring 1^a and the spider 1^b, supported thereon.

2 2 are threaded sockets in the ring 1^a, in which supporting-arms may be screwed. One 30 of these supporting-arms should be made hollow to form a pipe for the supply of gas when gas is to be burned in the lamp, all in accordance with the well-known construction as to such feature.

35 5 is any desirable form of burner supported on the burner-supports 3 and 4, one of which, 3, is hollow to connect with the hollow supporting-arm as a means of conducting the gas to the burner.

40 6 is the chimney, of glass or other translucent material, placed on the burner, which latter may be an ordinary Argand or other gas-burner, though preferably one designed to coöperate with the incandescent Welsbach 45 mantle 7, as shown.

The lamp is inclosed in a glass globe in which the bowl 8 forms the lower portion, while the hemispherical glass globe 9 forms the upper portion of said inclosing globe.

50 10 is a reflector of annular shape suspended from the supporting-frame and surrounding

the chimney 6, preferably, as shown, at a point about three-fifths of the way from the bottom to the top of said chimney.

11 11 are holes in the reflector near the outer circumference thereof for the passage of air-currents.

12 is a shield for the upper end of the chimney, preferably formed of translucent material—that is, glass or isinglass—cylindrical in 60 shape and depending from the under side of the supporting-frame, surrounding the upper end of the chimney, and extending to the upper side of the reflector.

13 is a deflector of annular shape supported 65 on the upper side of the ring 1^a and extending down nearly to the junction of the shield and the reflector, so as to leave an annular passage-way between the inner circumference of said deflector and the shield and the reflector, respectively.

14 14 represent flues, usually made of cast-iron tubes, mounted on the supporting-frame over the chimney and affording a passage-way for the escape of the hot gases of combustion. I preferably make these flues four 75 in number and surround the cluster with a metal casing 15, which has air-inlets 16 16 in its upper portion outside of the inclosing globe of the lamp.

80 17 is a bolt or piece of threaded pipe, and 18 is a nut coöperating therewith to hold the flues down upon the supporting-frame.

19 is a supporting-ring for the casing 15.

20 is a ring attached to the casing 15 and 85 having the packing-ring 21 for holding the globe 9 down in position and forming an air-tight joint for the same.

22 22 are air-passages left between the exterior of the flues 14 14 and the interior of the 90 casing 15.

The operation of my invention is as follows: Gas being admitted through the hollow pipe 3 and ignited at the burner, the flame produces an upward draft of hot gas, which 95 passes out of the flues 14 14. To supply the partial vacuum this produces in the bowl 8, air is drawn in through the inlets 16 16 and passes down into the passage-ways 22 22 in contact with the hot flues and thence into the 100 space within the upper bowl 9. In passing through the space within the globe the air is

forced by the deflector 13 to come in contact with the hot shield 12 and pass down upon the hot reflector 10. Passing along the upper side of said hot reflector the now thoroughly-heated air passes down through the holes 11 into the lower bowl and to the flame.

The advantages of the construction described are the thorough heating of the air supplied to the burner, the steady flow of said air produced by the deflecting-plates and passages, the protecting of the upper end of the chimney from side drafts by means of the shield 12 of translucent material, and, finally, by reason of the location of the incandescent mantle relative to the annular reflector the distribution of the light above and below the reflector.

Having therefore described my invention, what I claim as new, and desire to protect by Letters Patent, is—

1. In a lamp structure, the combination of a reflector, a gas-burner located below the reflector, an incandescent mantle located over said burner and projecting through the reflector, and a translucent shield surrounding the upper portion of the mantle.
2. In a lamp structure, the combination of a reflector, a gas-burner located below the

reflector, an incandescent mantle located over said burner and projecting through the reflector, a chimney arranged over said burner and mantle and projecting through the reflector, and a translucent shield surrounding said chimney and extending from the top of the reflector to a point above the top of the chimney.

3. In a lamp structure, the combination of a reflector, a gas-burner located below the reflector, an incandescent mantle located over said burner and projecting through the reflector, a chimney arranged over said burner and mantle and projecting through the reflector, a translucent shield surrounding said chimney and extending from the top of the reflector to a point above the top of the chimney, means for conveying the products of combustion from the lamp, and means for conveying highly-heated air to the interior of the lamp.

In testimony whereof I affix my signature in the presence of two witnesses.

MERTON P. STEVENS.
